UNITED STATES PATENT OFFICE.

LOUIS TUORTO, OF LANCASTER, PENNSYLVANIA.

PURSE-CLASP-LOCKING DEVICE.

No. 897,562.

Specification of Letters Patent.

Patented Sept. 1, 1908.

Application filed November 4, 1907. Serial No. 400,512.

To all whom it may concern:

Be it known that I, LOUIS TUORTO, a citizen of the United States, residing at Lancaster, in the county of Lancaster and State 5 of Pennsylvania, have invented new and useful Improvements in Purse-Clasp-Locking Devices, of which the following is a specification.

My invention relates to improvements in a 10 purse-clasp or frame whereby the purse may be locked without the use of a key and again readily opened.

The object of the invention is to provide a 15 purse-clasp or frame with secret mechanism, which clasp cannot be opened by any one without understanding the secret of said mechanism.

The purposes of the invention are attained by the mechanism, devices and means illustrated in the accompanying drawing, in which similar reference characters designate like parts throughout the several views, in which:—

Figure 1, is a side elevation of the front of 25 the purse frame or clasp, with a portion of the purse pouch removed and showing a portion of the hand-shaped cover, overlapping the operating or opening button, cut away. Fig. 2, is a side elevation of the same with the 30 forward portion of the covering hand removed and the rearward or hinged portion thereof appearing in section. Fig. 3 is an end elevation of the purse frame or clasp, as it appears when viewed from the left in Fig.

35 1. Fig. 4, is a vertical section of the purse frame or clasp, taken on the line $x-x$ in Fig. 1 and viewed from the left, as indicated by the arrow 1. Fig. 5, is a view of the purse frame or clasp in opened position, showing the 40 operating mechanism in the lower portion thereof. Fig. 6, is a vertical longitudinal section, taken on the line $y-y$ in Fig. 5, as it appears when viewed from the direction of the arrow 2.

45 In the drawing A designates the purse clasp or frame referred to in the opening paragraph hereto, in which a designates the rim of said clasp, which is made in two parts, A^1 and A^2 , hinged together by pivot pins a^1 , 50 with springs a^2 coiled about said pins a^1 and adapted to open said pivoted parts. Said rim is provided, at the required intervals, with orifices or holes a^3 , through which rivet pins a^4 are passed to secure the leather A^8 of 55 the purse pouch thereto, and over the leather A^8 , adjacent to the edge thereof, is placed a

metal strip a^5 with orifices a^6 formed therein, which latter orifices a^6 register with the orifices a^3 of the rim, to receive the ends of the rivet pins a^4 , securing the leather A^8 of the 60 purse pouch to said rim. To the inner surface of one of the hinged parts of said rim is secured a metal plate A^4 , supporting on its inner surface a sliding plate A^5 and a two-armed spring A^6 centrally pivoted on a stud 65 a^7 projecting inwardly from said metal plate A^4 , with one of its arms engaging against a stud a^8 projecting inwardly from said sliding plate A^5 , and the other arm in engagement with the stud a^9 projecting inwardly from 70 said metal plate A^4 , the arms of said spring serving to retain and move said sliding plate A^5 into a locked position. Said sliding plate A^5 terminating at its upper edge into an upwardly projecting arm a^{10} with a catch lip a^{11} 75 adapted to be engaged by an oppositely disposed catch lip a^{12} projecting inwardly from the opposite rim at the required point, locking the two parts of the rim together upon closing the purse.

80 Adjacent to the central edge of the sliding plate A^5 and secured to the inner surface of the metal plate A^4 is a keeper plate A^7 designed to engage the edge of said sliding plate A^5 , holding said sliding plate securely 85 in position. To the sliding plate A^5 are secured the thumb studs A^{11} and A^{15} which extend through slots formed in the plate A^4 , and which are designed for operating said plate. 90

95 In the plate A^4 near its center are formed the slots a^{13} and a^{14} placed at right angles to each other, and with relation to the purse members in a horizontal and vertical position respectively,—to receive the stud A^{11} ; the plate A^4 is also provided near its side and on a line with the guide stud a^{14} , with a horizontal slot a^{16} , through which extends the stud A^{15} . Also to the outer face of the plate 100 A^4 is hinged the embossed catch-cover A^8 , shown in the drawing as hand-shaped, which is formed with lugs a^{17} embracing corresponding lugs a^{18} extending at right angles from the outer face of said plate A^4 . Said catch-cover A^8 being secured by the hinge 105 formed by said lugs a^{17} and a^{18} in connection with a pivot pin a^{19} passed through aligned holes in said lugs and embraced between said lugs by a closed spring a^{20} , the ends of which are extended, one bearing against the outer 110 face of the plate A^4 and the other against the inner face of the catch-cover A^8 , thus tending

to keep the catch-cover A⁸ in an open position, or at right angles with relation to the face of the plate A⁴. To the back of the catch-cover A⁸ is secured transversely the plate A⁹ in such a manner that a recess is formed between the inner face of said plate A⁹ and the catch-cover A⁸ owing to the embossing of said catch-cover A⁸. Said plate A⁹ is adapted to be engaged and retained by the head A¹⁰ of the stud A¹¹ when the catch-cover A⁸ is in a locked position as shown in Fig. 6 of the drawing, thus completely covering and concealing said stud A¹⁰. A stud a²¹ is rigidly secured to the outer face of the plate A⁴ in a corresponding relation to the stud A¹⁵ for the purpose of puzzling the operator.

The operation of the device is as follows: The catch plate A⁵ is moved in a horizontal direction by pushing the stud A¹⁵ in the guide slot a¹⁶, which also simultaneously moves the stud A¹¹ in the guide slot a¹³, thus bringing the stud head A¹⁰ clear of contact with the catch-cover plate A⁹, releasing said catch-cover A⁸ and allowing it to spring outward actuated by the coiled spring a²⁰, thus exposing the stud-head A¹⁰ to view. The stud-head A¹⁰ is now pressed downward in a vertical manner, guided by the guide slot a¹⁴, thus forcing the projecting arm a¹⁰ and the catch-lip a¹¹ out of engagement with the catch-lip a¹² mounted upon the opposite rim, thus allowing the hinged members of the purse frame to fly open by the action of the spring a².

To close the device the hinged purse members are closed bringing the beveled portion of the catch-lips a¹¹ and a¹² into contact, thus depressing the catch-lip a¹¹ carried by the catch-plate A⁵ and guided by the vertical slot a¹⁴ until the purse members are closed, when the spring a⁶ forces the catch-plate A⁵ into its former position, thus bringing the catch-lips a¹¹ and a¹² into engagement and thus locking the purse members. The catch-cover A⁸ is now closed, bringing the catch-cover plate A⁹ into contact with the beveled head A¹⁰ of the stud A¹¹, thus forcing said stud A¹¹ carried by the catch-plate A⁵ in a horizontal direction, guided by the slot a¹³, thus allowing the catch-cover plate A⁹ to pass the stud head A¹⁰, after which the catch-plate A⁵ covering the stud A¹¹ flies back to its assigned position, thus bringing the stud head A¹⁰ into engagement with the catch-cover plate A⁹ securely locking said catch-

cover A⁸ in place and concealing the locking stud A¹¹ from view.

Having thus described my invention, what I claim as new and desire to secure by Letters Patent is:—

1. In a purse or bag frame of the class described, composed of two hinged members, one member formed with a frame-plate, carrying a movable catch-plate, formed with a rearwardly projecting catch-lip, and forwardly projecting actuating studs, projecting through guide slots in the frame-plate and terminating in beveled heads, means for retaining said catch-plate in a locked position, and means for concealing the head of the main or central stud for the purpose set forth.

2. In a purse or bag frame of the class described, the combination, of two hinged frame members, a frame-plate secured and forming part of one of said members, a movable catch-plate secured upon the inner surface of said frame-plate, a keeper-plate rigidly secured to the inner surface of said frame-plate, and partly overlapping said catch-plate, a spring-bearing stud mounted upon the catch-plate, a spring-bearing stud mounted upon the inner surface of said frame-plate, a spring-retaining stud mounted upon the inner surface of said frame-plate, a coiled spring embracing said spring-retaining stud, and having its extending ends in contact with the spring-bearing studs, for the purpose set forth.

3. In a purse or bag frame of the class described, comprising two hinged frame members, a frame-plate forming part of one of said members, guide slots extending through said frame-plate, hinge-lugs projecting from the outer face of said frame-plate, coacting with hinge-lugs formed upon an embossed catch-cover and pivoted to the same by a hinge-pin, a coiled spring embracing said hinge-pin and having extending arms, one bearing against the outer surface of the frame-plate and the other against the inner surface of the catch-cover, a catch-plate secured to the inner edge of the embossed catch-cover and a catch-stud formed with a head engaging the guide slots, for the purpose set forth.

In testimony whereof I affix my signature, in presence of two subscribing witnesses.

LOUIS TUORTO.
